(57) **CLAIM**

The ornamental design for a debris shield as shown and described.

DESCRIPTION

FIG. 1 is a top perspective view of a debris shield showing our new design;

FIG. 2 is another top perspective view thereof with the disclaimed vacuum port plug and retainer cap of the debris shield removed;

FIG. 3 a front elevational view thereof;

FIG. 4 is a right side elevational view thereof;

FIG. 5 rear elevational view thereof;

FIG. 6 is a left side elevational view thereof;

FIG. 7 is a top plan view thereof; and,

FIG. 8 is a bottom plan view thereof.

The portions of the debris shield shown in broken lines form no part of the claimed design. Portions of the debris shield shown in FIGS. 1-8 are shaded for transparency. The portions of the debris shield shown in FIGS. 1-8 that are not shaded for transparency are opaque.
